UNITED STATES PATENT OFFICE.

EDWARD SMITH, OF BRADFORD, ENGLAND.

MACHINE FOR PRODUCING WATER-MARKS ON FABRICS.

SPECIFICATION forming part of Letters Patent No. 709,368, dated September 16, 1902.

Application filed May 13, 1902. Serial No. 107,114. (No model.)

To all whom it may concern:

Be it known that I, EDWARD SMITH, a subject of the King of Great Britain and Ireland, residing at Bradford, in the county of York, 5 England, (whose postal address is 42 Well street, Bradford, aforesaid,) have invented certain new and useful Improvements in Machines for Producing Water-Marks on Fabrics, (for which I have obtained provisional protection in Great Britain, No. 21,894, 10 dated October 31, 1901,) of which the following is a specification.

The object of this invention is to deliver fabrics, hereinafter called "cloths," to the 15 pressure-rollers of calendering-machines in a novel manner by combining with said rollers mechanism for so operating upon the cloth that "water-marking" possessing a distinctive regularity of design or pattern is produced on the cloth and to substantially reproduce or repeat the same design throughout the entire length of the cloth and upon any number of pieces of cloth in duplicate, also to so operate parts of the combination 20 that designs of various configurations may be obtained and to repeat the same design or designs on similar cloths whenever afterward required instead of obtaining unknown and haphazard water-markings, such as are at 25 present produced on cloths operated upon in the ordinary and well-known methods hitherto in use.

My invention is especially applicable to that 30 class of cloths in which the ribs or cords run in the longitudinal direction of the cloth; but, as will be understood on reading the description and manner of operating the combination, the invention is also applicable to that 35 class of ribbed cloths in which the ribs run transversely, the guiding of the cloths being substantially the same in both cases.

In describing my invention in detail reference is made to the accompanying sheets of drawings, in which—

40 Figure 1 represents an end elevation of an ordinary calendering-machine with my improvement added thereto. Fig. 2 is a front-elevation of the same, partly in section; Fig. 3, a view at the opposite or driving end of the 45 machine, and Fig. 4 is a back elevation.

The end frames A of the calendering-machine rollers B and C, the latter commonly called "composite bowl," are of the ordinary description and form no part of my invention, each roller having a smooth and polished 55 circumference driven at the same surface speed by main driving-pulley D through spur-pinion E and spur-wheel E', the latter being keyed on the axle of metallic roller B, which is hollow and heated by steam or gas 60 in the ordinary well-known manner. The said roller driving the composite bowl C at the same surface speed by frictional contact. Pressure is put upon the roller B and composite bowl C by levers F, one mounted in 65 each end frame A and connected by the respective rods F' to levers F'', mounted at the top of machine. Passing through each of the last-named levers is a screw G, engaging with a circular nut G', mounted in the boss of lever for the purpose of transmitting pressure 70 to and for raising one roller clear of the other in the manner as hitherto when the machine is at rest.

The cloths to be water-marked are first 75 wound upon the beams H and J in a manner that the ribbed face of the cloths come together. These cloth-beams are carried by long axles H' and J', supported by suitable brackets K and K'. At each end of the said 80 axles a lever is mounted, and each lever is in contact with the end of two axles, as shown. A straight lever M is mounted at one end on a fulcrum-pin and a bell-crank lever M' on a similar fulcrum-pin at the other end of the 85 long axles. To the horizontal arm of bell-crank lever M' is attached a connecting-link N for coupling said arm to a lever O, mounted on a fulcrum-pin at O', the other end of said lever being connected to a spiral spring 90 P, held in tension, and between the fulcrum-pin O' and said spiral spring a small pulley Q is mounted on the lever O.

Upon the axle of the heated hollow metallic smooth-surfaced roller B a changeable 95 spur-wheel R is secured, gearing into a changeable spur-wheel R', mounted upon a stud secured to end of axle of composite roller or bowl C, and to the spur-wheel R' is secured a changeable tappet S, having one or more 100

suitably-shaped projections of configurations formed according to the desired pattern or design of water-marking to be given to the two pieces of cloth as they are simultaneously passed through the nip of the roller B and composite bowl C, the tension of the spiral spring P keeping the small pulley Q in contact with the contour of the revolving and changeable tappet S.

10 The two cloths T and T', rolled on the respective beams H and J, are delivered together face to face between the rotating smooth-surfaced heated metallic roller B and smooth-surfaced composite roller or bowl C, both rotating at the same surface speed, and in order to produce a water-marked design and repeat the same design throughout the entire length of each piece of cloth simultaneously an endwise - reciprocating horizontal movement is given to one or to both beams H and J and pieces of cloth wound thereon. In the drawings provision is made for reciprocally operating both beams horizontally in the bearings of brackets K K' in directions opposite to each other, so that the cloths T and T' are not always delivered to the rollers in a straight line—that is to say, at right angles to the nip of the roller B and composite bowl C—but at angles constantly varying in accordance with the differential contour of the revolving tappet S, one revolution of which simultaneously causes the production of the same water-marked design on two pieces of cloth, which is repeated on the cloths throughout the entire length of same, effected by the same horizontal movements of the cloths definitely controlled by the contour of the revolving tappet S. By horizontally reciprocating one or both beams H and J in the manner as described the ribs in the two cloths will in some places cross each other and pass into and through the nip of the rollers in a crossed condition where the crossed ribs are flattened by the pressure of the smooth-surfaced roller B and composite bowl C; but in other places, where the contour of the tappet S allows the cloths to be delivered with the ribs in the two cloths parallel to each other for a short distance and passed into the nip of the rollers in that condition, the ribs of the two cloths where parallel to each other will not be flattened by the pressure of the rollers, but each cloth for such distance will preserve its original plain rib or ground effect. By increasing and decreasing and thereby varying the rate of speed and distance given to the horizontal reciprocating movements of the carrying-beams and cloths T and T' the ribs of the two cloths are made to cross each other in some places more than in others and for the ribs of the two cloths to be delivered to the rollers parallel to each other for various short distances, in accordance with the contour of the revolving tappet S, thereby delivering the cloths T and T' to the roller B

and composite bowl in a manner for producing water-marks having a variable and like "watered" design upon the face of each cloth without any friction or rubbing action of the roller B or composite bowl C upon either piece of cloth, the crushing or flattening of the ribs producing lustrous water-marking wherever the ribs are allowed to cross each other and plain, with a ground-ribbed effect, where the ribs of the cloths pass parallel to each other into and through the nip of the rollers B and C. Suitable brakes, such as a leather or like strap U, passing over each cloth-beam H and J, with a weight W applied thereto, as shown, serve to keep the cloths T and T' in tension, also prevent overrunning, and allow the cloths to be fed uniformly to the smooth-surfaced roller B and composite bowl C of calendering-machine.

It will be obvious that my invention may be carried into effect by horizontally reciprocating one beam only—say, for example, beam H—and produce water-marking on the two cloths T and T' as they are passed between the roller B and bowl C, in which case the beam J would be allowed to rotate in its journals without any horizontal movement and the bottom arms of levers M and M' dispensed with, so that the top arms only of said levers would be in contact with the end of axle H', by which the beam H and cloth T would be horizontally reciprocated, the top arms of the levers M and M' being held in contact with the ends of axle H' by a rod connecting the two levers together in any suitable and well-known manner for the purpose.

The cloths T and T' as they leave the roller B and composite bowl C may be wound upon rollers, such as Y, rotated at the requisite speed in the usual manner by a belt engaging with small pulley Y', or cuttled by an ordinary cuttler Z, operated by a belt connection with pulley Z', disk crank Z², and connecting-rod Z³, arranged in the manner as hitherto.

What I claim as my invention is—

1. In combination in a machine for squeezing cloths, two smooth-surfaced rolls, a pair of cloth-carrying beams from which the cloths in duplicate pass between the rolls and means for reciprocating one of said beams longitudinally substantially as described.

2. In combination, a pair of smooth-surfaced rolls, a pair of cloth-carrying beams to deliver the cloths to the rolls in duplicate, a changeable tappet, means for driving the same and lever connections between the tappet and one of the beams for giving the same a longitudinal displacement substantially as described.

3. In combination, the smooth-surfaced rolls, a pair of cloth-carrying beams, each capable of longitudinal displacement and means for reciprocating the same reversely to each other, substantially as described.

4. In combination, the smooth - surfaced rolls, a pair of cloth-carrying beams, each capable of longitudinal displacement and means for reciprocating the same reversely to each other, said means comprising a tappet, a lever O operated thereby, levers M M' at the opposite ends of the rolls and arranged to engage the axle of each and the link connection

from the lever O to the lever M' for operating the same, substantially as described. 10

In witness whereof I have hereunto set my hand in the presence of two witnesses.

EDWARD SMITH.
